UNITED STATES PATENT OFFICE.

CHARLES F. SMITH, OF CHICAGO, ILLINOIS, ASSIGNOR TO MAXIM MANUFACTURING COMPANY, A CORPORATION OF ILLINOIS.

DISK FOR PEELING-MACHINES.

1,384,356.

Specification of Letters Patent. Patented July 12, 1921.

Application filed July 22, 1920. Serial No. 398,291.

To all whom it may concern:

Be it known that I, CHARLES F. SMITH, a citizen of the United States, and a resident of the city of Chicago, in the county of Cook and State of Illinois, have invented certain new and useful Improvements in Disks for Peeling-Machines; and I do hereby declare that the following is a full, clear, and exact description of the same, reference being had 5 to the accompanying drawings, and to the numerals of reference marked thereon, which form a part of this specification.

This invention relates more particularly to a disk for a peeling machine, for removing the skins from potatoes, carrots, beets or other similar vegetables by abrasion. Machines of this type have hitherto been constructed of a container having sharp ribs or file like striations on its inner periphery and 10 a rotating peeling disk having also sharp ribs or file like striations on substantially a flat surface except where the surface has been interrupted by rounded agitating humps. Such machines have been found 15 unsatisfactory for the reason that the ribs or striations especially on the rotating disk would often cut too deeply and would frequently remove too much peel from some 20 parts of the potatoes in rotating or turning over so that they would not be properly peeled, and the ribs or file like striations would be quickly worn to such a degree that 25 they failed to accomplish their function, and as they could not be resharpened, new parts 30 had to be substituted. In later types of machines, an abrasive substance such as the well-known carborundum has been used, but 35 in such cases it has been found that there has been considerable waste of the vegetables and this lack of efficiency has tended 40 greatly to reduce the popularity of such disks with the users. Further the flat surface of the disk intermediate the rounded lumps fails to produce the quickly desired 45 agitation of the potatoes to readily and satisfactorily present the different parts to the abrasive surfaces of the disk and container.

In my invention I have overcome these 50 defects by constructing the upper surface of the abrasive peeling disk with no flat parts upon its contour, and by grading the surface between various points so that the potatoes or vegetables which it is desired to peel are giving a swirling motion at certain periods. 55 This construction further allows me to use

any suitable abrasive surface on the disk such as concrete and carborundum for example, which rubs the skins from the potatoes by a kind of pecking and abrasive action.

It is therefore one of the objects of my invention to so construct the disk that the vegetables are thoroughly agitated by the peculiar contour of the abrasive surface.

It is a further object of this invention to 60 so grade the abrasive disk that the potatoes or vegetables are given a swirling motion as they are thrown outwardly away from the rotative axis by the centrifugal force of the rotating disk.

Other objects and advantages consist in the novel and peculiar structure of the abrasive part of the disk as will hereinafter be more specifically pointed out.

The invention (in a preferred form) is 70 illustrated in the drawings as hereinafter more fully described.

On the drawings:

Figure 1 is a section of an abrasive cylinder showing the disk in plan view and the 80 operating means therefor.

Fig. 2 is a section on line 2—2 of Fig. 1.

Fig. 3 is a section through the disk on line 3—3 of Fig. 2.

Fig. 4 is a section on line 4—4 of Fig. 2. 85

Fig. 5 is a development of the disk between the points A—B in Fig. 2 showing the rise from A to B in a counter clockwise direction, and

Fig. 6 is a perspective view of the disk. 90

As shown on the drawings:

Referring now more specifically to the drawings, in which similar reference characters denote similar features in the different figures, 1 denotes a cylinder having an 95 inner abrasive part. An abrasive disk 3 is rotatively supported within the cylinder and driven by any suitable means such as a motor 8 and intermeshing gears 9 and 10, for example.

In Fig. 2 to Fig. 6 I have shown an abrasive disk which embodies my invention. The disk comprises two parts, a lower member or base made of metal and an upper part of abrasive material such as a mixture of 105 concrete and carborundum. By using such a substance as concrete which is somewhat plastic and moldable before it becomes set, I am enabled to readily form the contour of the abrasive surface to produce the proper 110

agitation of the potatoes and the swirling motion. From the outer circumferential part of the disk the surface of the disk descends or slopes downwardly quite suddenly 5 at first and then more gradually until approximately the half way point to the rotative axis. The descending slope, it will be noted, is in the form of a curve. From approximately the half way point, the surface 10 has a gradual upward curve or slope until approximately the rotative axis is reached. The exact proportionment of parts, however, is immaterial as it is contemplated that various other proportionments might be used to 15 produce the same result. The gradual curve near the rotative axis has a tendency to cause the potatoes to more quickly move away from the rotative axis.

A very important feature of construction 20 of said disk, exists in constructing it with a plurality of vertically stepped portions, two of which are shown in the present embodiment of my invention. It will be noted that two partitions 4 and 5 have been secured in 25 the base of the disk. The upper surfaces of these partitions are curved approximately the same as the upper surface of the abrasive disk. The abrasive surface has been made flush with the top of the partition on one 30 side thereof, and on the other side of said partition the surface has only been made flush therewith at a point near the rotative axis, the rest of the surface on this side of the partition starts from a point below the 35 top of said partition and gradually rises until the top of the next partition is reached. In the present embodiment of my invention which shows two stepped portions, Fig. 5 shows the rise on the arc shown in Fig. 2, 40 from the lower side of partition 4 in a counter-clockwise direction to the partition 5. It will, therefore, be noted that while the upper surface of the abrasive disk has a continuously curved contour, it also 45 has a slope from one stepped portion to the other, as shown in Fig. 5. The combination of the curved contour with said last mentioned slope has a tendency to thoroughly 50 agitate the potatoes and give them a swirling motion. It will be noted that from the pit of one stepped portion near the rotative axis to the top of the next stepped portion, near its outer periphery, there is both a 55 radial and circular rise producing this swirling motion, which has a tendency to turn the potatoes. A plurality of drain holes 6 and 7 are made in the disk through which the dirt and peelings may be washed.

The operation is as follows:

60 The disk is rotated in a clockwise direction by any suitable means such as the motor and gears shown, after the requisite quantity of potatoes or similar vegetables have been placed in the cylinder. The centrifugal force created by the rapidly revolving

disk moves the potatoes outwardly into contact with the abrasive surface of the cylinder, but in so moving they encounter both the radial and circular inclines and are given a kind of swirling motion to thoroughly agitate them and turn them over to present different surfaces to the abrasive action of the disk and container. The vertically stepped portions which result from the particular surface contour of the disk 75 also assist in agitating the potatoes. The disk moves faster than the mass of potatoes in the container, and constantly causes the potatoes to turn as they drop over the acute stepped portion. In order to wash away the 80 dirt and peelings which have been removed, water or a similar wash may be directed over the potatoes in the container.

It will therefore be seen that I have devised an abrasive disk with a novel contour 85 on its abrading surface whereby the potatoes or vegetables are thoroughly agitated and the skins removed by a pure rubbing action.

While I have shown and described my invention in a preferred form, I am aware that many changes and modifications may be made therein without departing from the principles of my invention, and I therefore do not propose limiting the patent granted 95 thereon otherwise than necessitated by the prior art.

I claim as my invention:

1. In a device of the class described, an abrasive disk having a plurality of stepped 100 portions.

2. In a device of the class described, an abrasive disk having a plurality of stepped portions, the surfaces between said stepped portions being inclined.

3. A vegetable peeling disk comprising an abrasive member having a continuously curved contour on its upper surface, and provided with stepped portions, the formation between said stepped portions being 110 gradually inclined in one direction of rotation.

4. In a vegetable peeling machine, a rotary peeling disk having a contour of varying gradients whereby a swirling motion 11 may be imparted to a vegetable.

5. A peeling disk having vertical steps upon its upper surface, the circumferential portions between said steps having radial ascents and slopes whereby a swirling motion 12 is adapted to be imparted to a vegetable.

In testimony whereof I have hereunto subscribed my name in the presence of two subscribing witnesses.

CHARLES F. SMITH.
